UNITED STATES PATENT OFFICE.

LORINDA GALLAHER, OF WHEELING, WEST VIRGINIA.

FRUIT-JAR.

SPECIFICATION forming part of Letters Patent No. 278,530, dated May 29, 1883.

Application filed April 2, 1883. (No model.)

To all whom it may concern:

Be it known that I, LORINDA GALLAHER, a citizen of the United States, residing at Wheeling, in the county of Ohio and State of West Virginia, have invented certain new and useful Improvements in Fruit-Jars; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has for its object to provide an improved jar for preserves, pickles, and other canned articles, and aims to furnish a vessel for the purposes before described that will be convenient to fill, seal, and open, and will preserve the articles in a good condition.

It consists in a jar having an annular ridge near its top, the lid or cap having a depending annular flange, a sheet-metal band, and means for retaining this band in position, and in other improvements, all of which will be hereinafter described, and pointed out in the claims.

In the drawings, Figure 1 is an elevation of a jar provided with my improvements. Fig. 2 is a vertical section thereof. Fig. 3 is a perspective of the metal band and spring-bar, and Fig. 4 is a plan of the jar-lid.

My jar A is preferably made of the shape shown—that is, with its greatest diameter near its top at the point where it is provided with the annular ridge a, and tapering therefrom to its lower and to its upper side, as shown—as when so shaped the cap and the sheet-metal band, hereinafter described, may be more readily applied. It will be understood, however, that, where so desired, the jar may be made with vertical sides and provided with ridge a. The upper side of the ridge a is preferably made square, as shown, so as to provide a seat for the depending flange or rim of the cap.

The top plate, b, of the cap B is made of a size corresponding to the diameter of the upper end of the jar, and its depending rim b' is made of a length sufficient to permit it to rest down on the ridge a, as shown.

The sheet-metal band C is made in the shape of an inverted truncated cone, with its

lower side of a diameter corresponding to that of the jar at a point immediately below the ridge a, or less than the external diameter taken through the ridge, so that the band can not be slipped past the said ridge, and its upper side is made larger, so that it can extend up above the said ridge, as shown. On the upper side of the sheet-metal band I form a hook, c, and at a point diametrically opposite this hook I hinge one end of a spring-bar, D, which is adapted to be carried over the cap, and have its other end held by the hook c, when the several parts are arranged as will be described. This spring holds the sheet-metal band up against the jar, below the ridge a, and also forces the cap-piece into its bearing on the said ridge.

I intend to use my invention mainly on vessels made of porcelain or the common iron-stone china, as tin cans are objectionable, owing to their giving a bad taste to the contents, and vessels made of glass or stone are likely to be broken by extremes of heat and cold, though it will be understood that my invention could be employed on vessels made of such materials.

In the operation of sealing, after the jar has been filled, the cap B is placed on the same, and the metal band is drawn up from the bottom of the vessel, and the spring D is carried over the cap and secured by hook c, and the parts are in the position clearly shown in Fig. 2. The upper side of the band thus extends above the joint, and a channel is formed, extending entirely around the jar and over the joint between the depending rim of the cap-piece and ridge a. The melted wax is then poured in this channel and covers the joint, and the vessel is securely sealed.

Where so desired, instead of using the spring-bar D, other means could be employed for holding the cap or lid and the metal band in position—for instance, a coil-spring could be extended from side to side of the band, and adapted to be pushed aside when the band is being slipped into position, and then brought up over the cap or lid in substantially the same position as the bar D; but I prefer the latter, as it is more durable and easier operated.

When it is desired to open the vessel, the bar

D is unhooked and the band C is slipped down, carrying with it the sealing-wax or other sealing material, preventing the same from getting into the articles contained in the vessel. The rod D, it will be seen, is bent to provide the loops d d, which are convenient to receive the fingers when it is desired to use the said bar as a handle. The band is useful, in connection with the bar D or other suitable handle, as an attachment for jars either with straight sides or inclined from top to bottom. In the latter case the band will be made of a diameter less than the upper end of the jar, while in the former case a ridge, a, or other suitable retaining means may be formed on the jar, to prevent the band from slipping off the upper end of same. The bar passing over the can and bearing on the lid will also retain in place those lids which have the depending rim or flange projected down within the mouth of the jar.

Having thus described my invention, what I claim, and desire to secure by Letters Patent, is—

25 1. In a vessel for containing preserves or similar articles, the combination of the jar

having annular ridge near its upper end, the cap or lid having depending rim arranged to rest on said ridge, the sheet-metal band provided with the hook e, and the spring-bar having one end hinged to the band and carried over the cap or lid, and having its other end held by the hook e, substantially as and for the purposes set forth.

2. The vessel for containing preserves or 35 similar articles, consisting of the jar having annular ridge, the lid having depending rim, the band, and means whereby the band and cap or lid are held in position, all constructed and arranged substantially as set forth.

3. An attachment for jars, consisting of the band C, flared outward at its upper end, and a handle or spring-bar detachably secured to the upper edge of said band and adapted to be slipped upward on and bind upon the upper end of the jar, substantially as set forth.

In testimony whereof I affix my signature in presence of two witnesses.

LORINDA GALLAHER.
